UNITED STATES PATENT OFFICE

2,303,292

SHEET METAL SINK AND THE LIKE

Harry M. Heckathorn, Warren, Ohio, assignor, by
mesne assignments, to Steel Plumbing Wares,
Inc., Detroit, Mich., a corporation of Michigan

Application July 7, 1941, Serial No. 401,308

10 Claims. (Cl. 4—187)

My invention relates to sheet metal sinks and the like, and more particularly to enamel coated sheet metal sinks and the like, such as set forth in United States Patent No. 2,045,969, issued June 30, 1936, to Jacques Stanitz, for Sink, washbasin, and the like.

Such sheet metal sinks are formed from and in a single piece of sheet or plate metal, and then have applied thereto by usual methods a protective coating preferably of vitreous enamel.

The present invention relates still more particularly to such a sink and the like including a bowl, a splash back, and at least one drainboard at one side of the bowl, although frequently a drainboard is provided at each side of the bowl. The splash back extends the full length of the bowl and the drainboard or drainboards at the side or sides of the bowl, and a rolled rim extends around the ends and front of the bowl and drainboard or drainboards integrally from the splash back, and the rolled rim may extend downwardly in a skirt or apron.

Particularly in the case of such an enamel coated sheet metal sink including a bowl, a splash back, a single drainboard at one side of the bowl, and a rolled rim for the drainboard and bowl, it has been found that: the sheet metal structure may be formed and the vitreous enamel coating may be applied to the same to meet the most rigorous manufacturing standards and meet the most careful inspection in the factory; the sink may be packed for shipping in containers specially designed for the purpose by experienced container manufacturers; and yet after shipment, either immediately upon unpacking, or sometimes a relatively short time after installation, the enamel coating will craze and chip at the top of the rear curved bowl corner joining with the drainboard.

Investigation determined that the cause of this enamel crazing and chipping could not be directly attributed to the shippers, and the manufacturers of the containers in which the sinks were shipped made extended but unsuccessful efforts to produce a container which would solve the problem and enable the shipping of such enamel coated sinks and the like without the crazing and chipping of the enamel at the top of the curved rear bowl corner which joins the drainboard.

The objects of the present invention include the provision of an improved sheet metal sink and the like, preferably formed in a single piece of sheet metal, and including a bowl, a splash back, a drainboard at one side or both sides of the bowl, and a rolled rim for the drainboard and bowl, and

which includes further parts associated with the foregoing parts in such manner as to prevent crazing and chipping of the subsequently applied enamel coating particularly at the top of the rear bowl corner or corners which joins or join the drainboard, as the result of shipping the sink and the like in usual containers.

Further objects of the present invention include the provision of such an improved enamel coated sheet metal sink and the like, which is of simplified construction and arrangement, and is adapted for manufacture without requiring any changes in the methods of manufacturing the one piece sheet metal structure or carrying out the preferably vitreous enameling operation, and which reduces rejection during manufacture after the enameling operation due to warpage.

Further objects of the present invention include the provision of such an improved enamel coated sheet metal sink and the like which is so constructed and arranged as to enable it to be installed according to the usual methods of installing an enamel coated sheet metal sink and the like.

25 The foregoing and other objects are attained by the sheet metal sinks and the like, constructions, parts, combinations, and sub-combinations comprising the present invention, the nature of which is set forth in the following general statement, 30 preferred embodiments of which are set forth in the following description, and which are particularly and distinctly pointed out and set forth in the appended claims forming part hereof.

35 The nature of the improved sheet metal sink and the like of the present invention may be stated in general terms as including in a single drainboard sink and the like, preferably formed in a single piece of sheet or plate metal, a bowl, a splash back, and a drainboard at one side of 40 the bowl, and at the underside of the rear corner of the bowl joining the drainboard adjacent the splash back, one or more reinforcing members, preferably of formed sheet metal, secured as by spot welding at least to the drainboard and preferably both to the drainboard and the bowl, and a preferably vitreous enamel coating for the entire sheet metal structure.

45 In a double drainboard sink and the like, there may be a drainboard at each side of the bowl, and each rear corner of the bowl joining a drainboard may be provided with the improved reinforcements.

50 By way of example, several embodiments of the improved sheet metal sink and the like of the

present invention are illustrated in the accompanying drawings forming part hereof, in which

Figure 1 is a top plan view of a single drainboard sink including one embodiment of the present improvements, portions being broken away;

Fig. 2, a front elevation view thereof with portions broken away and shown in section;

Fig. 3, an end elevation view thereof with portions broken away and shown in section;

Fig. 4, an isometric view thereof, the sink being turned upside down for more clearly showing the present improvements;

Fig. 5, a view similar to Fig. 4, showing a double drainboard sink including a second embodiment of the present improvements, the nearer drainboard being shown in transverse section; and

Fig. 6, a view similar to Fig. 5, showing another double drainboard sink including a third embodiment of the present improvements.

Similar numerals refer to similar parts throughout the several views.

In Figs. 1 to 4 inclusive, a single drainboard sink indicated generally by 10 is illustrated and includes one embodiment of the present improvements.

The single drainboard sink 10 includes a single piece of formed sheet or plate metal, including a bowl indicated by 11, a single drainboard indicated by 12 at the right hand side of the bowl, as viewed from the front in the direction of the arrows in Fig. 1, an upright splash back indicated generally by 13, a rolled rim indicated generally by 14 extending around the ends and front of the drainboard and the bowl, and a ledge 14-1 extending between the back of the bowl and drainboard and the splash back which is offset from the bowl, all preferably according to the construction set forth in said Stanitz U. S. Patent No. 2,045,969. The drainboard 12, the rolled rim 14 and the ledge 14-1 taken together, may be termed the sink top.

The bowl 11 includes a bottom wall 15 having a drain opening 16 formed therein, a front wall 17, a back wall 18, and side walls 19 and 20.

A front curved corner 21 extends between the front wall 17 and the adjacent outer side wall 19 of the bowl. A rear curved corner 22 extends between the outer side wall 19 of the bowl and the back wall 18 thereof. A rear curved corner 23 of the bowl extends between the rear wall 18 and the inner side wall 20 thereof. A front curved corner 24 extends between the inner side wall 20 of the bowl and the inner front wall 17 thereof.

The rear curved corner 23 joins at its upper curved end 25 with the inner end 26 of the drainboard and with the ledge 14-1.

The upper end of the inner bowl side wall 20 and the upper end of the front curved bowl corner 24 similarly join with the inner end 26 of the drainboard and with the rolled rim 14.

The upper ends of the front wall 17, the front curved corner 21, and the outer side wall 19 join with the rolled rim 14; and the upper end of the rear curved corner 22 and the upper end of the back wall 18 of the bowl join with the rolled rim 14 and the ledge 14-1.

In a great many instances, after shipping, an enamel coated sink structure as set forth in said Stanitz U. S. Patent No. 2,045,969, the upper end of the rear corner of the bowl in a single drainboard sink, corresponding to the upper end 25 of the curved corner 23 which joins the

inner end 26 of the drainboard 12, would have the enamel coating thereof crazed or chipped upon unpacking or would develop a craze or chip soon after unpacking and frequently soon after installation. Similar but less frequent enamel crazing and chipping were experienced with double drainboard sinks.

In one container recommended and provided by a container manufacturer, the container generally was a rectangular box having a removable top, the box fitting the outer dimensions of the sink, with sufficient space for layers of corrugated paper fillers and supporting members and the like.

A partition was provided having an aperture fitting the outer dimensions of the bowl which depended through the aperture.

Other filling and supporting reinforcements of corrugated paper were supplied for the partition in an effort to ship the sink without damage.

Single drainboard enamel coated sheet metal sinks and the like, made according to said Stanitz U. S. Patent No. 2,045,969, and shipped in containers as above described, and in all other containers recommended for trial, were all subject more or less to the objectionable crazing and chipping of the enamel at the upper end of the rear bowl corner joining the drainboard.

It was thought possible that relative vibration might be induced between the corner 23 of the bowl and the sink top during shipping, and that this relative vibration might cause the enamel crazing and chipping.

It was discovered that by maintaining the bowl corner 23 and the sink top rigid with respect to each other, that the objectionable crazing and chipping of the enamel coating during shipping was prevented.

In the sink 10, the means for maintaining the bowl corner 23 and the sink top rigid with respect to each other include a formed reinforcing strut indicated generally by 27 which is located on the underside of the sink 10, and which is curved to fit around the outer and underside of the corner 23 of the bowl and the outer and underside of the bowl inner wall 20 and the bowl back wall 18.

The reinforcing strut 27 is preferably made of formed sheet metal, and at its upper end is provided with angled feet 28 and 29, the foot 28 abutting the underside of the inner end 26 of the drainboard 12 and the angled foot 29 abutting a portion 30, which as shown is a downwardly protruding portion, of the ledge 14-1.

The lower end of the reinforcing strut 27 is provided with a flange 31 fitting the curve of the bowl corner 23, and the feet 28 and 29 and the curved flange 31 are secured respectively to the drainboard inner end 26, the ledge portion 30, and the bowl corner 23, preferably by spot welding.

The reinforcing strut 27 is secured to the bowl on the underside of the top and bowl of the sink prior to the application of the enamel coating, which is subsequently applied in the usual manner.

The single drainboard enameled coated sheet metal sink 10 including its reinforcing strut 27 may be shipped in a usual container, subject to the usual jars and vibrations of shipping, without producing the undesired crazing or chipping of the enamel coating at the upper end of the rear bowl corner 23 joining the drainboard 12.

In Fig. 5 is illustrated a double drainboard

sink indicated generally by 110 which includes a second embodiment of the present improvements.

The double drainboard sink 110 includes, formed in a single piece of sheet or plate metal, a bowl indicated generally by 111, drainboards indicated generally by 112a and 112b at the opposite sides of the bowl, an upright splash back indicated generally by 113, a rolled rim indicated generally by 114 extending around the ends and front of the drainboards and the bowl, and a ledge 114-1 extending between the back of the bowl and drainboards and the splash back which is offset from the bowl, all preferably according to the construction set forth in said Stanitz U. S. Patent No. 2,045,969. The drainboards 112a and 112b, the rolled rim 114, and the ledge 114-1 taken together may be termed the sink top.

The bowl 111 includes a bottom wall 115, side walls 119 and 120, and a rear wall 118.

A curved rear corner 122 extends between the side wall 119 and the rear wall 118, and a curved rear corner 123 extends between the rear wall 118 and the side wall 120.

The drainboards 112a and 112b have inner ends 126a and 126b joining the upper end of the bowl side walls 119 and 120, respectively.

As shown, the ledge 114-1 has portions 130a and 130b, which as shown are downwardly protruding portions, the portion 130a being adjacent the corner 122 and the portion 130b being adjacent the corner 123.

In the sink 110, the means for maintaining the rear bowl corners 122 and 123 and the sink top rigid with respect to each other include a plurality of reinforcing struts each indicated generally by 127, and each including at its upper end an angled foot 128 and at its lower end an angled flange 131.

One of the struts 127 extends angularly between the underside of the inner end 126b of the drainboard 112b and the outer side of the bowl side wall 120 adjacent the bowl corner 123, and the foot 128 is secured to the drainboard end 126b preferably by spot welding, and the flange 131 is secured to the bowl side wall 120 preferably by spot welding.

Similarly, one of the struts 127 extends angularly between the underside of the ledge portion 130b and the outer side of the bowl rear wall 118, adjacent the corner 123, and its foot 128 and flange 131 are secured respectively to the ledge portion 130b and the bowl rear wall 118, preferably by spot welding.

Similarly another of the struts 127 extends angularly between the underside of the ledge portion 130a and the bowl rear wall 118 adjacent the corner 122, and its foot 128 and flange 131 are secured respectively to the ledge portion 130a and the outer side of the bowl rear wall 118, preferably by spot welding, and another strut 127 extends and is secured between the underside of the inner end 126a of the drainboard 112a and the bowl side wall 119.

After the one piece formation of the sink 110 and the struts 127 are secured to each other, the sink structure is then provided with the enamel coating in the usual manner.

In Fig. 6 is illustrated another double drainboard sink indicated generally by 210 which includes a third embodiment of the present improvements.

The double drainboard sink 210 includes a one piece sheet metal formation identical with

that of the sink 110, including a bowl indicated generally by 211 and having rear curved corners 222 and 223, drainboards indicated generally by 212a and 212b at opposite sides of the bowl 211, a splash back 213 and a ledge 214-1 between the splash back and the bowl 211, and a rolled rim 214 around the ends and front of the drainboards and bowl.

The drainboards 212a and 212b, the rolled rim 214 and the ledge 214-1 taken together may otherwise be termed the sink top.

In the sink 210, the means for maintaining the sink top rigid with respect to the rear bowl corners 222 and 223 include curved channel members indicated generally by 227a and 227b. The channel member 227a extends around the bowl corner 222 on the underside of the sink top and has a curved web 232a secured preferably by spot welding to the underside of the drainboard 212a and the ledge 214-1. The curved channel reinforcing member 227a also includes extending from opposite sides of the curved web 232a, curved flanges 233a and 234a.

Similarly, the curved channel reinforcing member 227b extends around the bowl corner 223 on the underside of the sink top and has a curved web 232b secured preferably by spot welding to the underside of the drainboard 212b and the ledge 214-1.

After the one piece formation of the sink 210 and the reinforcing channels 227a and 227b are secured together, the sink structure is then provided with the enamel coating in the usual manner.

Both the sinks 110 and 210 after shipping are free from the undesired crazing and chipping of the enamel coating at the upper ends of the rear bowl corners.

After experiments with a limited production had determined that the improved sinks 10 and 110 and 210 after shipping were free from the undesired crazing and chipping of the enamel coating at the upper ends of the rear bowl corner, regular production of the improved sinks 45 was engaged in.

Previous to the use of the improved sink structures of the present invention, considerable rejection had been encountered after the enameling operation due to warpage resulting in imperfect enamel coatings.

The best production in one plant of applicant's assignee through the enameling operation was 1100 sinks a day of one piece sheet metal sinks without the present improved reinforced construction.

By the use of the present improved sink structures, no difficulty is now encountered in supporting the sinks in the enameling ovens, the sinks holding their shapes throughout the various heats.

This unexpected result enables a production of 1700-1800 properly enameled sinks having the improved structures in the same plant which previously could only produce 1100 properly enameled sinks of the prior construction.

In the foregoing description, certain terms have been used for brevity, clearness and understanding; but no unnecessary limitations are to be implied therefrom, or from the use of such words in the claims; and such terms are intended to be broadly construed as follows:

The word "sink" used herein and in the claims is intended to include sinks, washbasins, washbowls, and the like; the words "sheet metal" is intended to include sheet and plate metal of the

desired or necessary gauge; the words "rolled rim" are not intended to imply an arcuately shaped rim, since the rim may have any desired shape, such as illustrated, which is not entirely arcuate, and may terminate with either a shallow skirt as illustrated, or a deep skirt; and the words "enamel coated" are intended to refer to and include coatings other than vitreous enamel coatings which may have similar characteristics to enamel coatings.

The embodiments of the present improvements illustrated and described herein are by way of example, and the scope of the present invention is not limited to the same or to the particular details thereof, but is commensurate with any and all novel subject matter contained herein which may at any time properly under the patent laws be set forth in the claims hereof or originating herein, and the elements of any such claims are intended to include their structural or functional equivalents.

I claim:

1. In an enamel coated sheet metal sink and the like, a sink top, a bowl depending in one direction from the sink top, and a rear splash back extending in an opposite direction from the sink top, the sink top including a drainboard at one side of the bowl, and the bowl including a rear curved corner having its upper end joining the drainboard, and reinforcing means secured to the sink top adjacent to said rear curved corner at opposite sides thereof for maintaining the sink top and the rear curved bowl corner rigid with respect to each other.

2. In an enamel coated sheet metal sink and the like, a sink top, a bowl depending in one direction from the sink top, and a rear splash back extending in an opposite direction from the sink top, the sink top including a drainboard at one side of the bowl, and the bowl including a rear curved corner having its upper end joining the drainboard, and reinforcing means secured at said rear curved corner to the sink top and the bowl for maintaining the sink top and the rear curved bowl corner rigid with respect to each other.

3. In an enamel coated sheet metal sink and the like, a sink top, a bowl depending in one direction from the sink top, and a rear splash back extending in an opposite direction from the sink top, the sink top including a drainboard at one side of the bowl, and the bowl including a rear curved corner having its upper end joining the drainboard, and reinforcing means for maintaining the sink top and the rear curved bowl corner rigid with respect to each other, the reinforcing means including a pair of struts extending between the underside of the sink top and the outside of the bowl adjacent and on opposite sides of the rear corner, each strut having an end foot abutting and being secured to the underside of the sink top and a flange abutting and being secured to the bowl.

4. In an enamel coated sheet metal sink and the like, a sink top, a bowl depending in one direction from the sink top, and a rear splash back extending in an opposite direction from the sink top, the sink top including a drainboard at one side of the bowl, and the bowl including a rear curved corner having its upper end joining the drainboard, and reinforcing means for maintaining the sink top and the rear curved bowl corner rigid with respect to each other, the reinforcing means including a curved strut extending around the rear curved corner of the bowl on the out-

side thereof beneath the sink top, the strut having a plurality of feet abutting and being secured at opposite sides of said rear curved corner to the underside of the sink top, and a curved flange coextensive with said strut abutting and being secured to the outside of the rear curved bowl corner.

5. In an enamel coated sheet metal sink and the like, a sink top, and a bowl depending in one direction from the sink top, the sink top including a drainboard at one side of the bowl, and the bowl including a curved corner having its upper end joining the drainboard, and reinforcing means for maintaining the sink top and the curved bowl corner rigid with respect to each other, the reinforcing means including a pair of struts extending between the underside of the sink top and the outside of the bowl adjacent and on opposite sides of the corner, each strut having an end foot abutting and being secured to the underside of the sink top and a flange abutting and being secured to the bowl.

6. In an enamel coated sheet metal sink and the like, a sink top, and a bowl depending in one direction from the sink top, the sink top including a drainboard at one side of the bowl, and the bowl including a curved corner having its upper end joining the drainboard, and reinforcing means including a curved strut extending around the curved corner of the bowl on the outside thereof beneath the sink top, the strut having a plurality of feet abutting and being secured at opposite sides of said curved corner to the underside of the sink top, and a curved flange coextensive with said strut abutting and being secured to the outside of the curved bowl corner.

7. In an enamel coated sheet metal sink and the like, a sink top, a bowl depending in one direction from the sink top, and a rear splash back extending in an opposite direction from the sink top, the sink top including a drainboard at one side of the bowl, and the bowl including a rear curved corner having its upper end joining the drainboard, the sink top and the bowl and the splash back being formed in a single piece of sheet metal, and reinforcing means adjacent said rear curved corner and secured to the sink top at opposite sides of said curved corner for maintaining the sink top and the rear curved bowl corner rigid with respect to each other.

8. In an enamel coated sheet metal sink and the like, a sink top, a bowl depending in one direction from the sink top, and a rear splash back extending in an opposite direction from the sink top, the sink top including a drainboard at one side of the bowl, and the bowl including a rear curved corner having its upper end joining the drainboard, the sink top and the bowl and the splash back being formed in a single piece of sheet metal, and formed sheet metal reinforcing strut means secured at said rear curved corner to the sink top and the bowl for maintaining the sink top and the rear curved bowl corner rigid with respect to each other.

9. In an enamel coated sheet metal sink and the like, a sink top, and a bowl depending in one direction from the sink top, the sink top including a drainboard at one side of the bowl, and the bowl including a curved corner having its upper end joining the drainboard, the sink top and the bowl being formed in a single piece of sheet metal, and formed sheet metal reinforcing means adjacent said curved corner and secured to the sink top at opposite sides of said curved corner

for maintaining the sink top and the curved bowl corner rigid with respect to each other.

10. In an enamel coated sheet metal sink and the like, a sink top, and a bowl depending in one direction from the sink top, the sink top including a drainboard at one side of the bowl, and the bowl including a curved corner having its upper end joining the drainboard, the sink top

and the bowl being formed in a single piece of sheet metal, and formed sheet metal reinforcing means secured at said curved corner to the sink top and the bowl for maintaining the sink top and the curved bowl corner rigid with respect to each other.

HARRY M. HECKATHORN.
